Primary Examiner—Catherine Tuttle(74) *Attorney, Agent, or Firm*—Cislo & Thomas LLP(57) **CLAIM**

The ornamental design for a bird novelty, as shown and described herein.

DESCRIPTION

FIG. 1 is a front view of my bird novelty;

FIG. 2 is a rear view thereof;

FIG. 3 is a right side elevational view thereof with the left side elevational view being a mirror image thereof;

FIG. 4 is a top view thereof; and,

FIG. 5 is a bottom view thereof.

The broken lines immediately adjacent the shaded surfaces of the wings and circular body portion define the bounds of the claim. All other broken lines are for illustrative purposes only. None of the broken lines form part of the claimed design.
